UNITED STATES PATENT OFFICE.

ANNA M. SHELDON, OF PAWTUCKET, RHODE ISLAND.

DOLL.

Application filed June 9, 1921. Serial No. 476,294.

To all whom it may concern:

Be it known that I, ANNA M. SHELDON, a citizen of the United States, residing at Pawtucket, in the county of Providence and 5 State of Rhode Island, have invented certain new and useful Improvements in Dolls, of which the following is a specification.

My invention relates to dolls and the purpose of my invention is to provide a doll to 10 the head of which may be attached rosettes, flowers (real or artificial), bows, and other ornaments, without the necessity of the use of pins.

I accomplish this object by the device 15 shown in the accompanying drawing in which—

Figure 1 shows the bust and head of a doll having thereon an ornamental bow attached by means of my invention.

20 Figure 2 is a part of the head of a doll showing the receiving portion of my device, and

Figure 3 a cross-section through the head 25 of the doll and the attaching device and ornamental bow on the line $x-y$ of Figure 1.

My device is in substance the ordinary 30 commercial snap-fastener, of which the receiving portion is imbedded in or secured to the substance of the doll's head, while to 35 the entering portion may be attached artificial or natural flowers, rosettes, bows of ribbon, or the like, by having the same sewed to such entering portion.

35 In Figure 3, a' is a section of a portion of the head of the doll showing the receiving member O of my device imbedded therein, and in the same figure, E is the entering portion of my device, B' being the section of 40 the bow attached to said entering portion.

The operation of my invention is obvious 45 from the drawings and consists simply in attaching by proper means the ornamental bow which is to be secured to the doll's head, to the entering portion of the ordinary commercial snap-fastener, and snapping it into 50 the receiving portion of the fastener which is imbedded in the doll's head, thus forming a secure connection between the ornament and the head which connection is concealed by the bow or other ornament, and can be removed and changed at will.

As dolls are used mostly by children, and as the use of pins in order to fasten bows and other ornaments to the head of a doll is 55 objectionable from the danger arising through the careless use of the same by children, it will be at once seen that my invention provides a perfectly safe and convenient method for attaching ornaments to the 60 doll's head without any danger whatever to the child using the doll.

Where a doll's head is made of cloth or material which can be sewed, the receiving portion of the snap-fastener may be attached 65 to the head by sewing.

Where the head of the doll is made of plastic material, such as papier mâché, or other molded or moldable substance, the receiving portion of the fastener is easily inserted into the head while the same is being molded; while in the case of dolls having heads composed of hard substances, the fastener may be inserted either by leaving a proper indentation when the doll is manufactured, or by the subsequent perforating 75 of the head and the use of cement between the receiving portion and the head of the doll.

It is also evident that more than one of my 80 devices may be used upon the same head so that a number of ornaments may be connected at the same time to the head of the doll.

Having described my invention what I claim and desire to secure by Letters Patent 85 is:—

In means for attaching an ornamentation to the head of a doll, a doll head formed of solid material having a socket therein opening at the outer side of the head, an apertured keeper member of a snap-fastener being of plate formation and embedded in the head adjacent the surface thereof with the aperture registering with the head socket, and an entering member of the snap-fastener 90 carrying a suitable ornamentation removably received in the apertured keeper member.

In testimony whereof I affix my signature in presence of two witnesses.

ANNA M. SHELDON.
